Inventor,

Charles M. Smith,
by Crosby Gregory Atty.

UNITED STATES PATENT OFFICE.

CHARLES M. SMITH, OF BOSTON, MASSACHUSETTS, ASSIGNOR TO LEWIS J. BIRD, TRUSTEE, OF SAME PLACE.

CAR-PLATFORM.

SPECIFICATION forming part of Letters Patent No. 366,518, dated July 12, 1887.

Application filed September 10, 1886. Serial No. 213,242. (No model.)

To all whom it may concern:

Be it known that I, CHARLES M. SMITH, of Boston, county of Suffolk, and State of Massachusetts, have invented an Improvement in 5 Car-Platforms, of which the following description, in connection with the accompanying drawings, is a specification, like letters on the drawings representing like parts.

This invention has for its object to provide 10 railway-cars with platforms made compressible or yielding, to prevent said cars from telescoping in case of collision.

My improved platform is especially adapted 15 for use on passenger-cars of that class shown and described in the application, Serial No. 180,949, filed October 26, 1885, and in which the body of the car is composed of metal plates riveted together, the floor of the said car being supported upon keelsons secured thereto and 20 to the lower part of the car-body; but my invention is applicable to cars made of wood.

The particular and novel features of my invention will be hereinafter pointed out in the claims at the end of this specification.

25 Figure 1 is a side elevation of a portion of a railway-car provided with my improved platform; Fig. 2, an end view of Fig. 1 with the car-body omitted; and Fig. 3 is a top or plan view of Fig. 1 below line x x , to clearly show 30 the construction of my improved platform.

The car or body A herein shown is supposed 35 to be composed of numerous sheets or plates of metal riveted together, substantially as shown and described in the application before referred to, the floor of the said car being supported upon keelsons e e' , secured thereto and 40 to the car-body. Each outside keelson, e' , is prolonged beyond the end of the car-body to sustain the platform a' , having usual steps, a^2 , supported by hangers a^3 .

Each keelson e' supports a bar, b , flanged at 45 its ends and forming part of a compressible frame to support the platform a' , one end of said bar being secured to a buffer-beam, b' , forming the front of the compressible frame, the other end of said bar having a larger flange, as b^2 , the said bar being fitted into a guideway in the said keelson. The flange b^2 of each bar, as herein shown, has an ear, b^4 , (see dotted lines, Fig. 3,) to which is secured a cross-head, c .

The cross-head c has fastened to it bars c' , also secured to the buffer-beam b' , the said cross-head and bars forming part of the compressible frame, the said bars constituting a 55 support for a buffer-box, c^3 , sustaining a buffer, c^4 , extended through the beam b' and having the usual disk, c^5 .

The buffer c^4 projects through the buffer-box c^3 toward the car, and is provided with a 60 head, c^6 , against which presses one end of a buffer-spring, d , the said spring being herein shown as encircling a rod or bar, d^2 , extended through the cross-head c and attached to the car-body, as shown in Fig. 3. 65

The cross-head c and flanges b^2 of each bar b are provided with openings, through which are extended rods or bars d' , firmly secured to a cross-beam, d^2 , preferably bearing against the ends of the keelsons e and against angle- 70 irons d^4 , fastened to the keelsons e' . 75

Each rod or bar d' , as clearly shown in Fig. 3, is encircled by an auxiliary or platform spring, f , preferably of steel, the said springs in practice being made so as to possess an 80 aggregate resisting power of forty tons (more or less) when occupying their normal uncom- 85 pressed position, (shown in Fig. 3,) the cross-head c and flanges b^2 being held against the springs by usual nuts, d^5 , on the bar or bolts d' . 90

The bars b and c' are united by strengthen- 95 ing-bars h , and the compressible frame is still further strengthened by the braces h' , joining each bar b with the cross-head c . The bars h and h' are both secured to the bars b by a bolt, h^2 , extended through a slot, h^3 , (see Fig. 1,) in the keelson e' .

In case of collision, the force of the shock will first be received by the buffer-disk c^4 and then by the buffer-beam b' . As the buffer c^4 is forced backward toward the car, the spring d will be compressed, the said spring being sufficient to resist all ordinary shocks sustained by it in coupling or suddenly stopping the train. When, however, the force is suffi- 95 cient to overcome the resistance of the spring d , as in case of collision, the said force will be resisted, as herein shown, by the springs f , the said force being transmitted from the buffer-beam b' to the said spring through the compressible frame referred to, the aggregate resistance of said springs being in practice pref- 100

erably as much as forty tons uncompressed and over sixty tons when compressed. The bars *b*, forming part of the compressible frame referred to, will move in the guideway of the 5 keelsons *e'* as the springs *f* are compressed.

As an additional means to resist shocks which would completely compress the buffer-spring *d* and would otherwise somewhat change the platform, I have provided braces *h'*, only 10 one of which is shown, the said braces, preferably of steel, being secured to the buffer-beam *b'* and the car-body, as shown in Fig. 1.

I claim—

1. In a car-platform, a compressible frame, 15 constructed substantially as described, a buffer supported by the compressible frame, and the buffer-spring *d*, combined with independent auxiliary or platform springs *f*, to act upon the said frame and normally maintain it rigid 20 and unaffected until after the stress of the buffer-spring shall have been overcome by slight shocks, substantially as specified.

2. In a car-platform, a compressible frame composed of the cross-head *c*, a buffer supported by the compressible frame, the buffer-beam *b'*, and bars joining said buffer-beam and cross-head, combined with the buffer-spring *d* and with independent platform-springs *f*, acting against the cross-head *c* to 30 resist the movement of the said compressible frame, substantially as described,

3. In a car-platform, the keelsons *e'*, provided with a guideway, a compressible frame composed of the cross-head *c*, the beam *b'*, the 35 bars *b*, movable in said guideway, and auxiliary bars to strengthen said compressible

frame, combined with the buffer-spring *d* and the springs *f*, to operate substantially as described.

4. In a car-platform, a compressible frame 40 composed of the cross-head *c*, the buffer-beam *b'*, and bars joining said beam and cross-head, and the buffer-box *c'* and buffer supported thereby, combined with the spring *d*, to resist shocks upon the buffer, and with the springs *f*, 45 to resist shocks upon the compressible frame, substantially as described.

5. In a car-platform, the keelsons *e'*, provided with a guideway, a compressible frame composed of the cross-head *c*, the buffer-beam 50 *b'*, the bars *b*, movable in said guideway, the bars *c'*, the buffer-box secured thereto, and a buffer supported by said buffer-box, combined with the spring *d*, to resist shocks upon the buffer, and with the springs *f*, to resist shocks 55 upon the compressible frame, substantially as described.

6. In a car-platform, a compressible frame composed of the cross-head *c*, the buffer-beam 60 *b'*, and bars joining said buffer-beam and cross-head, the buffer-box *c'*, and buffer supported thereby and by the buffer-beam, combined with the spring *d* and with the brace or braces *h'*, to operate substantially as described.

In testimony whereof I have signed my name 65 to this specification in the presence of two subscribing witnesses.

CHARLES M. SMITH.
